UNITED STATES PATENT OFFICE.

ROBERT H. RUSSELL, OF WORLAND, WYOMING.

FRAMING BEVEL.

Application filed May 29, 1922. Serial No. 564,420.

To all whom it may concern:

Be it known that I, ROBERT H. RUSSELL, a citizen of the United States, residing at Worland, in the county of Washakie and State of Wyoming, have invented certain new and useful Improvements in Framing Bevels, of which the following is a specification.

The present invention appertains to improvements in carpenters' tools, known more particularly as framing bevels, and it has for its primary object to provide a convenient device especially useful in laying off of certain rafters entering into building constructions.

It may be well to explain that although the steel square is probably the most used of all carpenters' tools, and in spite of the fact that this tool is capable of being effectively employed in rafter framing, comparatively few of its users are sufficiently conversant with it to enable its employment for this purpose, particularly in the framing of hips, valleys, jacks and other cripple rafters. It is, therefore, my object to devise a handy tool in the form of a bevel having blade members thereon, each bearing proper data for the use of the square and so formed as to be quickly set for use in the laying off of a rafter for the usual set pitch or pitches and which without further adjustment serves for marking off the plumb and side cuts of jacks and other cripples.

More particularly speaking, my invention embodies a stock or handle and a plurality of blades adjustable to make predetermined angles with respect to the stock, the edges of each blade having a definite fixed angular relation to the stock such that one edge may be utilized for the marking off of plumb cuts while the other of these edges, without altering the angular adjustment, will serve for the marking off of cheek or side cuts. In those devices of this character which have heretofore been proposed, this is only capable of being accomplished by a change of the adjustment of the blades and therefore with my means of operation the laying off of angles is greatly facilitated. With the above and other objects in view, the invention consists in certain combinations and arrangements of the parts as will more fully appear as the description proceeds, the novel features thereof being pointed out in the appended claims.

In the drawing:

Figure 1 is a side elevation of a framing bevel constructed in accordance with this invention, the blades being in normal closed position.

Figure 2 is an edge view thereof.

Figure 3 is a side elevation showing the blades opened to their particular angle-marking position.

Figure 4 is a longitudinal sectional view on the line 4—4 of Figure 1.

Figure 5 is a detail plan view of one of the blades and showing the data contained by this one instructing in regard to the use of the steel square.

Figure 6 is a detail perspective view of the combined stop and ferrule forming a part of this invention.

Corresponding and like parts are referred to in the following description and indicated in all of the views of the drawings, by like reference characters.

Referring to the drawing, 1 designates the body portion or stock of the bevel device which is provided with a central slot 2 of sufficient size to receive a plurality of blade members, generally indicated by the reference character 3, there being in the present instance five of such blade members, a blade for each of the following roof pitches:

One-quarter, one-third, three-eighths, five-twelfths, and one-half, these blades being designated *a*, *b*, *c*, *d*, and *e*.

The blades are pivotally secured to the end of the stock upon the pintle 4 having a thumb nut or head 5 by means of which the member may be adjusted to produce a sufficient amount of friction to hold the blades in their particular adjusted positions. For this purpose the pintle 4 passes through a ferrule 6 which embraces the stock on three sides, this ferrule being cut away at the end so as to form a stop shoulder 7 which is common to all of the blade members.

The opposite end of the bevel is preferably provided with a metal protector 8 so as to prevent splitting of the stock. One side of the handle is cut away as indicated at 9 to permit ready access to the blades for opening the desired one, each blade having a fingernail notch 10 to facilitate the opening operation.

Referring particularly to Figure 3, it will be observed that each individual blade has

the same general configuration but the blades vary in width so as to present two distinct marking edges, one indicated α and the other γ . In other words, these two edges 5 when the blade is opened to its adjusted position with the shoulder 11 thereof abutting against the stop shoulder 7 of the ferrule have a distinct angular relation with respect to the inner edge α of the stock. 10 Furthermore, the edge γ bears a distinct relation to the edge α as will be borne out in the further description of the use of this device.

Each of these blades bears upon its face 15 the data which the carpenter may desire or require instructing him in the use of the steel square by means of which the laying off of the various rafter constructions is facilitated. In the illustrated case the data relates 20 to the calculations which are required for laying off plans of a roof of one-quarter pitch and, therefore, the next blade in the implement herein illustrated would contain the data for a roof of one-third pitch, and 25 so on.

In the use of this simple device it will be understood from the foregoing general description that in the laying off of the common rafters for a one-quarter pitch roof, 30 the blade α is pulled outwardly until its shoulder 11 abuts against the stop shoulder 7. This is the predetermined position for marking off of the proper angles of the common rafters. The thumb nut 5 is preferably tightened to hold the blade in this position whereupon the bevel is laid upon the rafter to be marked as desired. Marking along the edge α will give the angle line for a plumb cut. Without changing the 35 angular relation of the blade with respect to the stock the bevel may now be used for marking off the side or cheek cuts, the edge γ being employed for this purpose. It thus follows that the edge γ gives the proper 40 angle for side cuts when the edge α is used for marking the plumb cuts so that there is a definite relationship between these two edges in the use of the blade. This same 45 relationship exists throughout the remaining blades and I, therefore, have in a single implement all that is required for laying off of angles in the general set pitches of roofs that are customarily employed in building 50 constructions at this time.

55 As hereinbefore premised, in the known constructions it is necessary to adjust the single blade bevel member for each marking operation, and it is necessary to determine the position which the blade is to occupy with relation to the stock before the laying off of the angles can be performed. In those types of known bevels using a plurality of blades it is necessary to read-

just the various blades in order to get one or the other of the cuts which are here obtainable by a single adjustment so that my improvements form an important advance in tools of this character by means of which the laying off of angles is greatly facilitated.

Having thus described my invention, what 70 I claim as new and desire to secure by Letters Patent is:

1. A framing tool comprising a stock, a blade member pivotally connected thereto, the marking edges of which when the blade 75 is set bear different angular relations to the stock, and fixed stop means for predetermined the set to be given the blade for laying off the particular angles prescribed by said edges. 80

2. A framing tool comprising a stock and a blade member connected thereto for movement relative to the stock, and having opposite marking edges bearing an angular relationship to each other, each edge being disposed for marking off an angle line bearing a known relationship to the angle line for which the other edge serves as a marking edge in the successive use of the edges of 85 the blade when in predetermined relation to the stock. 90

3. A framing tool comprising a stock, and a blade member pivotally connected thereto the operative marking edges of which converge toward the pivot for the blade, each 95 edge having a definite angular relationship with respect to the stock such that one edge may be employed for marking off plumb cuts while the opposite edge may be employed for marking off side cuts. 100

4. A framing tool comprising a stock, a blade member pivotally connected thereto and formed with a stop face, a cooperating stop upon said stock limiting the opening movement of the blade to a definite angular position, said blade having opposite marking edges which when the blade is set with the stops in contact bear different angular relations to the stock and determine the set to be given the blade for laying off particular angles prescribed by said edges. 105

5. A framing tool of the class described comprising a stock, a plurality of blades pivotally secured to one end thereof, each blade being constructed and formed to serve 110 in cooperation with an edge of said stock for marking off of angles for a definite roof pitch, a stop member on said stock common to said blades for predetermined the position thereof in the laying off of the angles 115 prescribed for each blade, each blade having a portion adapted to abut against said stop member and means for holding said blades in adjusted positions relative to said stop. 120

In testimony whereof I affix my signature.
ROBERT H. RUSSELL.
